ALBERT VASZI, OF MILWAUKEE, WISCONSIN

REFRACTORY GRATE FOR FURNACES

Application filed March 6, 1926. Serial No. 92,752.

This invention relates to improvements in refractory grates for furnaces.

It is an object of this invention to provide for a furnace having an oil burner, a refractory grate removable as a unit from the combustion chamber of such furnace for the purpose of facilitating replacement of the refractory material and permitting continued operation of the burner during such replacement.

10. It is a further object to provide a refractory grate movable as a unit vertically relative to such burner to thereby control the intensity of the heat generated by the burning oil.

15. Another object is to provide a refractory grate incorporating in one unit structure designed to accomplish either of the previously noted objects at the will of the operator.

Other objects in addition to those noted above will appear as the description progresses.

In the drawings:

Fig. 1 is a fragmentary, vertical, sectional view of a furnace showing the combustion chamber with a removable, refractory grate therein.

Fig. 2 is a fragmentary, vertical, sectional view taken on the line 2—2 of Fig. 1.

30. Fig. 3 is a fragmentary view of a portion of the refractory grate.

Fig. 4 is a sectional plan view of the grate taken on the line 4—4 of Fig. 2.

Like parts are identified by the same reference characters throughout the several views.

35. The furnace 1 is provided with an ordinary combustion chamber 2 having the usual feed doorway 3 and door 4. Beneath such chamber is an ash pit 5 having the usual draft opening 6 and draft door 7. Positioned within the chamber 2 is an oil burner 8 (represented diagrammatically) and having an oil supply line 9 extending through the door 4.

40. The removable refractory grate unit is designated generally by the numeral 10 and comprises a supporting framework 11 and refractory grate 12 carried thereby. The supporting framework comprises an upper rectangular frame portion 13 and a lower rectangular frame portion 14. Frame portions 13 and 14 are connected by a plurality of uprights 15

and 16 each of which are elongated rectangular tubes. The frame portions 13 and 14 are also secured together by corner members 17. Frame portions 13 and 14 and corner members 17 comprise angle irons. The invention, 55 however, is not confined to the particular shape of parts shown in the drawings, it being obvious that numerous modifications may be adopted.

The supporting framework 10 is mounted 60 upon rear wheels 18 and front wheels 19, the latter of which are preferably pivoted to the framework to facilitate steering movement when removing the refractory grate 12 from or replacing it in the ash pit 5 as will be subsequently more specifically set forth.

Slidably journaled in each of the uprights 16 is a rack bar 20 arranged in sets upon each side of said frame and slidably journaled in each of the uprights 15 is a rod 21 disposed at 70 the ends of said frame. Rack bars 20 and rods 21 are each pivotally connected at 22 to the grate platform or bed 23 which comprises an integral structure having spaced longitudinal T-shaped sections 24. The pivotal connections 22 are preferably made to accommodate any inequalities of distances between the pivotal bearings that may arise when raising and lowering the refractory grate 12 as will subsequently be described.

80. Fig. 3 is a fragmentary view of one of the T-shaped sections 24. Each section is preferably provided with a series of recesses 25 within which pins 26 may be positioned to extend above the upper surface of the sections. 85 Mounted upon the sections 24 and extending transversely thereof are a plurality of refractory bricks 27 each having a hole adapted to receive a pin 26, thereby spacing the bricks 27 from adjacent bricks upon the corresponding sections 24. Positioned upon each of the bricks 27 is a refractory brick 28 having a hole adapted to receive a portion of pin 26. The bricks 28 extend longitudinally of their respective sections 24 and are each spaced 95 from adjacent bricks 27 upon adjacent sections 24.

Thus a plurality of openings extending between the sections 24 and the refractory bricks 27 and 28 is provided through which 100

air may pass to mingle with the vaporizing oil given off by the burner 8.

Extending longitudinally and horizontally of the supporting frame 10 is a pair of shafts 29 and 30 each positioned upon opposite sides of the frame and provided with bearings 31 secured to the uprights 16. The bearings 31 are arranged in pairs, each bearing of a pair being upon opposite sides of an upright, thereby providing spaces upon the shafts 29 and 30 to which gears are secured each meshing with a rack bar 20. Each shaft may be rotated alternatively and the bars 20 thereby controlled and moved vertically in sets. It is, of course, understood that the uprights 16 are each slotted at 33 to permit the gears 32 to mesh with their respective bars 20. At the front of the framework 10 and secured to each shaft 29 and 30 is a ratchet wheel 34 co-operating with a pawl 35 pivoted to the framework to prevent rotation of the shafts in one direction for the support, through gears 32 and rack bars 20, of the refractory grate 12. A crank 36 may be mounted alternatively upon the extended ends of shafts 29 and 30 which may thereby be rotated to raise or lower the grate 12.

It will also be noted that the forward end of the lower frame portion 14 is provided upon each side with a set screw 37 extending laterally of the framework and engageable with the sides of the ash pit 5 to thereby hold the grate 12 and its supporting frame work 10 in position within the ash pit.

Rods 21 are provided for the purpose of assisting the rack bars 20 in steadyng the grate frame or bed 23 against longitudinal movement.

In operation, when the refractory bricks 27 and 28 have been destroyed by the heat generated in the combustion chamber 2, the set screws 37 are operated to release the framework 10 from the walls of the ash pit 5, whereupon the refractory grate unit may be passed through the doorway 6 to the exterior of the ash pit. If it so happens that the refractory grate 12 is elevated to a height (see dotted line 38 in Fig. 1) which will not permit the unit to be removed through doorway 6, then the grate 12 is lowered by first releasing one of the pawls 35 and rotating the corresponding shaft 30 in the proper direction to lower one side of the grate and then releasing the other pawl 35 to permit rotation of its corresponding shaft 30 to lower the other side of the grate. When the grate has been lowered sufficiently, it may then be removed from the ash pit as noted previously.

Fig. 2 illustrates the action that takes place when the refractory grate is being lowered or raised. One side of the grate will be lowered or elevated before the other side. For this reason the pivotal connections of the rack bars 20 and rods 21 are each provided with elongated bearing slots 39 extending trans-

versely of the grate platform or bed 23, thereby compensating for the inequality of distances between the pivotal connections 22 when the plane passing through such connections varies from the horizontal. It is obvious that other arrangements than that just described for the pivotal connections between the grate platform 23 and the rack bars 20 and rods 21 may be provided, it being deemed sufficient disclosure to represent one form.

When the refractory grate unit has been removed from the ash pit 5, the refractory bricks 27 and 28 may be removed from the pins 26 where necessary and replaced by new material. When the deteriorated bricks have been replaced by new ones, the unit may then be moved through doorway 6 into the interior of the ash pit and anchored in position by means of the set screws 37. The refractory grate 12 may then be raised to its proper position relative to the burner 8 by manual operation of the shafts 29 and 30 as indicated previously.

The outstanding advantage of the structure just described lies in the fact that the refractory grate 12 may be removed for repairs from the combustion chamber 2 without stopping the operation of the burner 8. The efficiency of the burner will, of course, be impaired while the grate 12 is removed but the removable grate obviates the necessity of shutting off the burner as would otherwise be necessary where an ordinary grate is provided and is in need of repairs.

It is also apparent that proper adjustment between the burner and grate may be obtained by the invention disclosed herein and thus insure intense combustion at all times.

While I have shown and described but one form of my invention, it is to be understood that I recognize that there are several forms that may be adopted without departing from the spirit of this invention. I, therefore, do not limit myself to the form shown.

I claim:

1. A refractory grate unit for oil burning furnaces having an ash pit provided with a doorway, said unit comprising a framework, wheels supporting the frame, certain of the wheels being movable about a vertical axis, whereby the frame may be steered, a grate bed supported by said framework for movement vertically relative thereto, means carried by said framework for moving said grate bed vertically relative to said framework, and a removable refractory grate supported by said bed, said unit being passable through said doorway and receivable in said ash pit.

2. A refractory grate unit for oil burning furnaces having an ash pit provided with a doorway, said unit having a framework, wheels supporting the frame, certain of the wheels being movable about a vertical axis, whereby the frame may be steered, a remov-

able refractory grate supported by said framework, said unit being passable through said doorway and receivable in said ash pit, and adjustable securing means carried by said framework for releasably engaging the walls of said ash pit, whereby said unit may be removably secured in said ash pit.

3. A refractory grate unit for oil burning furnaces having an ash pit provided with a doorway, said unit comprising a framework, wheels supporting the frame, certain of the wheels being movable about a vertical axis, whereby the frame may be steered, a grate bed supported by said framework for movement vertically relative thereto, means carried by said framework for moving said grate bed vertically relative to said framework, a removable refractory grate supported by said bed, said unit being passable through said doorway and receivable in said ash pit, and adjustable securing means carried by said framework and engageable with the walls of said ash pit.

4. A refractory grate unit for oil burning furnaces, said grate comprising a frame provided with supporting wheels, a grate bed, bars guided by said frame for vertical movement and connected with said grate bed, said bars being arranged in sets at opposite sides of said frame each movable independently and one of said sets being pivotally and slidably connected with said bed, and means for moving said bars.

5. In an oil burning furnace, the combination with an oil burner, of a grate bed movable vertically relative to said burner, means for moving said bed vertically, and refractory material removably supported by said bed.
